UNITED STATES PATENT OFFICE.

JOHN ROGER, OF DENVER, COLORADO.

ORE-ROASTING FURNACE.

SPECIFICATION forming part of Letters Patent No. 677,701, dated July 2, 1901.

Application filed February 12, 1901. Serial No. 47,086. (No model.)

To all whom it may concern:

Be it known that I, JOHN ROGER, a subject of the King of Great Britain, residing at Denver, in the county of Arapahoe and State of Colorado, have invented new and useful Improvements in Ore-Roasting Furnaces, of which the following is a specification.

This invention relates to ore-roasting furnaces, and it includes certain fundamental features hereinafter set forth.

The ordinary manner now employed for delivering ore to a roasting-furnace is to drop the ore from the top arch onto the hearth or to supply it from a point above and at one side of the hearth. These are decidedly objectionable, as during the descent of the ore it crosses the draft of the furnace, and as the draft is always high much of the fine material is caught thereby and is carried away, thereby causing a great loss. By my improved furnace, however, these losses are wholly avoided. My ore-feeding means are situated below or substantially below the hearth and deliver the ore upward into the furnace for treatment thereby, and this being the case there is no possibility of any part of the moving mass coming in contact with the draft, so that no waste in ore during its supply to the hearth can possibly ensue.

The ore-underfeeding mechanism is exceedingly simple and is capable of maintaining an adequate supply of the ore, and it also evenly distributes the same along the hearth, and while the invention is in no wise limited to any particular kind of device or apparatus for feeding the ore onto the hearth from below the same I find a spiral conveyer or screw advantageously adapted to this function, the conveyer or screw tapering toward one end thereof, so that the reduced end thereof being unable to carry the ore forward as fast as it is fed forward by the larger end of said screw the ore will be naturally elevated along the length of the screw, being simultaneously fed to the hearth and distributed across the same.

The invention is represented in one embodiment thereof in the accompanying drawings, forming a part of this specification, wherein—

Figure 1 is a cross-sectional elevation of an ore-roasting furnace involving my invention. Fig. 2 is a sectional plan view of said furnace.

Fig. 3 is an enlarged sectional elevation of one end of the feed-screw. Fig. 4 is an elevation of the screw, showing a different form thereof.

In the drawings I have shown a portion of a familiar type of ore-roasting furnace in which my underfeeding mechanism is incorporated and will now briefly describe the same, it being understood, of course, that the improvements may be employed with equal facility in other kinds of ore-roasting furnaces.

The numeral 12 indicates the roasting-chamber, 13 the hearth thereof, and 14 the arch, the ore being sustained upon the hearth when exposed to the action of the heat in the roasting-chamber.

As hereinbefore stated, the ore is fed upward onto the hearth and simultaneously distributed uniformly along the same, and while any suitable device may be employed for this purpose I find a tapered feed-screw, as 15, highly advantageous for securing the desired functions. That end of the feed-screw which receives the ore is the larger, and said screw gradually tapers from said end to the opposite one. The feed-screw is located in a casing or boxing, as 16, substantially V-shaped in cross-section and having oppositely-disposed lateral flanges, as 17, along its upper edges, which may be suitably embodied in or secured to the hearth 13. The casing 16, and hence the feed-screw inclosed thereby, lies transversely of the furnace, and by reason of the shape of the casing an elongated discharge-opening 15' is formed upon the top or upper side of the same, through which the ore is positively fed and distributed. The front end of the casing is flanged, as at 18, and a shelf or bracket, as 19, is connected to said flange and supports a boxing or bearing for receiving one end of the feed-screw shaft and a vertical shaft, as 20. The opposite end of said feed-screw shaft has a wear-piece 21, engaged by a screw, as 22, carried by the bearing 23, bolted or otherwise secured to the rear end of the casing 16, said rear end being flanged, as at 24, to fit within a squared opening in the brickwork of the furnace, suitable fastening devices extending through said flange into the brickwork. The inner end of the casing 16 is covered by a cap or plate, as 25, having an opening, as 26, through which the

ore can pass, the ore gravitating from a hopper, as 27, of suitable size and supported in some convenient manner. The plate 25 has lugs 25' on its under side, adapted to fit snugly 5 against the inner face of the trough-shaped casing 16. A chute or supply-tube, as 28, depends from said hopper, and its delivery end is in proximity to and over the charging-opening 26. The crushed ore therefore 10 descends from the hopper 27 into the chute 28, from which it is discharged into the trough-shaped casing 16, where it is met by the tapered feed-screw 15, and as the latter rotates it advances the ore laterally of the furnace 15 and at the same time lifts it onto the hearth 13.

Any suitable mechanism may be employed for driving the underfeed-screw, a system of intermeshing gears being shown for this purpose 20 connected to the shafts hereinbefore mentioned.

The horizontal feed-screw shaft carries a bevel-gear, as 15', meshing with a coaxial bevel-gear 20' on the lower end of the vertical shaft 20, while said shaft 20 carries at its upper end a bevel-gear, as 20", meshing with a co-operating gear 30' on the horizontal and suitably-supported line-shaft 30, the latter carrying a driving member, as the pulley 31. Said pulley may be connected by a belt (not shown) with a motor or other power-furnishing device. When the shaft 30 is rotated, the feed-screw 15 will be through the agency of the intermediate parts rotated, so as to supply the ore to the hearth. The ore is supplied in some suitable manner to the hopper 27, from whence it passes to the communicating chute 28, gravitating from the latter onto the feed-screw 15, the flow of the mass 35 through the chute being regulated by a hand-valve, as 35, of the "slide" type, intersecting said chute. The ore will be taken by the rotating feed-screw and advanced transversely or crosswise of the furnace and at the same 40 time caused to rise and pass through the lon-

gitudinal opening 16' in the top of the casing 16. As the feed-screw is of progressively-decreasing cross-sectional area from its front to its rear end, the reduced or smaller part thereof will be insufficient to carry the ore forward as fast as it is delivered from the larger part of said feed-screw, so that the ore is caused to rise along the complete length of the screw and to enter the furnace-chamber and to be simultaneously and uniformly distributed along the hearth 13, it being understood, of course, that the larger end of the feed-screw is kept fully supplied with material from the chute 28.

As shown in Fig. 4, the thread of the screw 60 may be omitted at intervals, thereby to reduce friction on the gearing, besides securing an even distribution if an insufficient amount of material is fed.

Having described the invention, I claim— 65

1. In an ore-roasting furnace, a roasting-hearth and a feed-screw located below and co-extensive with the hearth transversely thereof, said feed-screw being tapered from its ore-receiving end toward its opposite end. 70

2. In an ore-roasting furnace, a roasting-hearth, and a feed device located below the hearth and coextensive with the same transversely thereof, constructed and arranged to elevate the ore onto said hearth and simultaneously to distribute the same across said hearth. 75

3. In an ore-roasting furnace, a roasting-hearth and a feed-screw located below the hearth having portions of its thread removed, 80 and of progressively-decreasing taper from its ore-receiving end to the opposite end thereof.

In testimony whereof I have hereunto set my hand in presence of two subscribing witnesses.

JOHN ROGER.
